(57) CLAIM

The ornamental design for a wave form shoe rack, as shown and described.

DESCRIPTION

FIG. 1 is a left upper frontal perspective view of a first embodiment of the design for a wave form shoe rack; FIG. 2 is a left side elevation view of the design for the wave form shoe rack of FIG. 1 showing, in phantom, multiple shoe boxes stored thereon, the right side elevation being a mirror image.

FIG. 3 is a top plan view of the design for the wave form shoe rack of FIG. 1 and FIG. 9.

FIG. 4 is a bottom plan view of the design for the wave form shoe rack of FIG. 1 and FIG. 9.

FIG. 5 is a front plan view of the design for the wave form shoe rack of FIG. 1.

FIG. 6 is a rear plan view of the design for the wave form shoe rack of FIG. 1.

FIG. 7 is a left side elevation view of the design for the wave form shoe rack of FIG. 9 showing, in phantom, multiple shoe boxes stored thereon, the right side elevation being a mirror image.

FIG. 8 is a front plan view of the design for the wave form shoe rack of FIG. 9.

FIG. 9 is a left frontal perspective view of a second embodiment of the design for a wave form shoe rack; and FIG. 10 is rear plan view of the design for the wave form shoe rack of FIG. 9.

The portions of the drawings in FIGS. 2 and 7 shown in dashed lines form no part of the design of this invention.
